CENTRIFUGE BUCKET

James R. Hiltner, Nahant, Mass., assignor to
General Electric Company, a corporation of
New York

Application September 9, 1933, Serial No. 688,813

12 Claims. (Cl. 118—49)

The present invention relates to centrifuge buckets such as are used in the manufacture of rayon, for example.

The object of my invention is to provide an improved centrifuge bucket which is highly resistant to centrifugal stress so that it is capable of operating at high speed, which is resistant to acid, and which is capable of being manufactured at low cost.

For a consideration of what I believe to be novel and my invention, attention is directed to the accompanying description and the claims appended thereto.

In the drawing, Fig. 1 is a side elevation, partly in section, of a centrifuge bucket embodying my invention, and Fig. 2 is a similar view of modification.

Referring to the drawing, 1 indicates the body of the centrifuge bucket and 2 indicates the hub. The body comprises a shell 3 made of suitable metal such as steel or aluminum. It may be made by die casting, for example. In metal body 3 are a plurality of rows or rings of spaced holes 4 of a size larger than the holes required for the escape of acid when the bucket is used for spinning rayon. Shell 3 is reinforced by one or more layers of steel wire 5. For this purpose I may use piano wire of suitable diameter. The steel wire is wound on the shell in groups between the rows of holes 4 whereby there is provided a group of turns of reinforcing wire in each space between the rows of holes. The groups of turns may be independent of each other or the groups of turns may be formed of one continuous wire, the wire extending downwardly from one group to another between openings 4. The turns are wound on the shell under sufficient tension to strongly reinforce the shell and they are preferably united to the shell and to each other by fused metal. For example, the turns may be soldered to the shell and to each other. There is thus provided a metal shell which is reinforced by steel wire, the wire in turn being united to and forming in substance an integral part of the shell. There is thus provided a metal shell which is strong but which at the same time is relatively light in weight.

On the shell and wire, both inside and outside, is a covering 7 of non-metallic material which is hard and acid resisting and which adheres to metal and also to a material comprising spinnable textile fibres united by an artificial resin, such as a phenolic condensation product. Preferably, I use hard rubber but I may use other materials such as for example a suitable baking varnish

or enamel. In the present instance, in the drawing I have indicated hard rubber. The hard rubber extends through openings 4 in the shell so that the edges of the openings are covered by the rubber. On the rubber covering 7 is a covering 8 comprising spinnable textile fibres, preferably a number of layers of cloth, united by an artificial resin, such as a phenolic condensation product. Covering 8 adheres to covering 7 and thus through it is united to the metal shell 3. This serves to give a smooth, hard, acid resisting finish to both the inside and outside of the body 1. Extending through the body are holes 9 which are located at the centers of holes 4 in metal shell 3. There are thus provided holes 9 which are formed entirely in the non-metallic material of the bucket.

The hub of the bucket comprises a metal sleeve 10 formed integral with shell 3, a covering 11 comprising material similar to the material of covering 7, for example, hard rubber, on its outer surface and a covering 12 of spinnable textile fibres, probably layers of cloth, united by an artificial resin, such as a phenolic condensation product. By this arrangement, the metal sleeve forms a liner for the hub.

In making the bucket, the coverings 7 and 11 and the coverings 8 and 12 are applied or molded directly on the metal shell. The methods for applying or molding materials of this type are known and need not be described in this specification. Any suitable method or methods may be used.

If found desirable, the reinforcing wire for the shell may be omitted, in which case the shell itself may be made of material somewhat heavier than would otherwise be the case. Such a construction is shown in Fig. 2 wherein 15 indicates the metal shell, 16 the non-metallic covering, such as the hard rubber covering, and 17 the covering comprising textile material united by an artificial resin.

By my invention, I provide a centrifuge bucket which is unusually strong and which is acid resisting, the metal being entirely covered by acid resisting material. The non-metallic covering 7 serves as a means for protecting the metal and also as a means for uniting shell 3 to covering 8. And in turn, covering 8, being stronger than covering 7, serves to prevent covering 7 from being thrown off by centrifugal force. Also, spinnable textile fibres united by an artificial resin, when molded, acquire a very smooth glossy finish, a thing most desirable in a rayon spinning bucket.

What I claim as new and desire to secure by Letters Patent of the United States, is:

- 5 1. A centrifuge bucket comprising a metal frame, reinforcing wire wound on the outside of said frame, an outer covering of spinnable textile fibres united by an artificial resin, and a covering of non-metallic material between the metal frame and wires and the first named covering which serves to unite the first named covering to the metal frame and wire.
  - 10 2. A centrifuge bucket comprising a metal frame having circumferentially extending rows of spaced holes therein, reinforcing wire wound on the outside of said frame between the rows of holes, a covering of hard non-metallic material over the frame and wire and extending through said holes, and a covering of spinnable textile fibres united by an artificial resin on said first named covering.
  - 15 20 3. A centrifuge bucket comprising a metal frame having circumferentially extending rows of spaced holes therein, reinforcing wire wound on the outside of said frame between the rows of holes, the turns of said wire being united to each other and to the frame by fused metal, a covering of hard rubber over the frame and wire and extending through said holes, and a covering of spinnable textile fibres united by an artificial resin on said hard rubber, said coverings being provided with holes in line with but of smaller diameter than the holes in the metal frame.
  - 25 35 4. A centrifuge bucket comprising a metal frame having circumferentially extending rows of spaced holes therein, reinforcing wire wound on the outside of said frame between the rows of holes, and a covering of hard non-metallic material over the frame and wire and extending through said holes, said covering being provided with holes in line with but of smaller diameter than the holes in the metal frame.
  - 40 45 5. A centrifuge bucket comprising a metal frame having spaced holes therein, a covering of non-metallic material over the frame and extending through said holes, and a covering of spinnable textile fibres united by an artificial resin on said first-named covering, said coverings being provided with holes in line with but
- of smaller diameter than the holes in the metal frame.
6. A centrifuge bucket comprising a metal frame having spaced holes therein, a covering of hard rubber over the frame and extending through said holes, and a covering of woven fabric united by an artificial resin on said hard rubber covering, said coverings being provided with holes in line with but of smaller diameter than the holes in the metal frame.
  - 10 7. A centrifuge bucket comprising a metal frame, reinforcing wire wound on the outside of said frame and united thereto by fused metal, and a covering of non-metallic material over said frame and wires.
  - 15 8. A centrifuge bucket comprising a metal frame, reinforcing wire wound on the outside of said frame, a covering of hard rubber over the frame and wires, and a covering of spinnable textile fibres united by an artificial resin on said hard rubber.
  - 20 9. A centrifuge bucket comprising a body and a hub, said body comprising a metal frame having a covering of non-metallic material and of spinnable textile fibres united by an artificial resin, and said hub comprising a metal liner integral with said frame and provided on its outer surface with a covering of hard rubber and spinnable textile fibres united by an artificial resin.
  - 25 10. A centrifuge bucket comprising a metal frame, an outer covering of spinnable textile fibres united by an artificial resin, and a covering of non-metallic material between the metal frame and the first named covering which serves to unite the first named covering to the frame.
  - 30 35 11. A centrifuge bucket comprising a metal frame, a covering of non-metallic material over the frame and integrally united thereto, and a covering of spinnable textile fibres united by an artificial resin on said first named covering and integrally united thereto.
  - 40 45 12. A centrifuge bucket comprising a metal frame, a covering of hard rubber over the frame, and a covering of woven fabric united by an artificial resin on said hard rubber covering, said metal and coverings being integrally united to each other.

JAMES R. HILTNER.
